(57) **CLAIM**

The ornamental design for a light, as shown and described.

DESCRIPTION

FIG. 1 is a perspective view of the light according to the
present invention.

FIG. 2 is a front view of the light according to the present
invention. The rear view and the right and left side views are
identical to the front view for the claimed invention.

FIG. 3 is top view of the light according to the present
invention; and,

FIG. 4 is a bottom view of the light according to the present
invention.

The broken lines are for illustrative purposes only and form
no part of the claimed design.
